ADJUSTABLE HALTER

Original Filed June 24, 1929

Inventor

Ivanhoe Winslow

By *Clarence O'Brien*, Attorney

UNITED STATES PATENT OFFICE

IVANHOE WINSLOW, OF SHERIDAN, MONTANA

ADJUSTABLE HALTER

Application filed June 24, 1929, Serial No. 373,326. Renewed January 31, 1931.

This invention relates to improvements in halters and has for its primary object the provision of an adjustable halter adapted to fit a cow or horse, and is of simple construction, permitting quickly and easily placing the halter upon a horse or cow head and as readily removed therefrom, strong, inexpensive, durable and otherwise well adapted to the purpose designed.

10 Other objects and advantages of the invention will become apparent during a study of the following description, taken in connection with the accompanying drawings, wherein:

15 The figure illustrated is a perspective view of a halter embodying my invention and showing application to the head of a horse.

With reference more in detail to the drawings it will be seen that the horse's head is 20 designated generally by the reference character 5. The preferred embodiment of my invention as herein illustrated consists of a nose strap 6 being in the nature of an endless strap and is thereby especially designed 25 for insuring strength and durability. As illustrated the nose strap 6 is adapted to be passed through a pair of rings 7 and 8 respectively. A chin strap 9 is looped or bent upon itself as illustrated to receive the rings 30 7 and 8 and is provided in its length with suitably spaced openings 10 to receive the tongue of the buckle 11 to permit said strap to be readily lengthened or shortened when desired, so as to fit the horse's or cow's head 35 according to the various sizes of the head. Suitable endless cheek straps 12 and 13 respectively are adapted to receive the respective rings 7 and 8 and extend upwardly therefrom. As illustrated the cheek straps 40 12 and 13 have their intermediate portions stitched together so as to render the said straps sufficiently strong to withstand the usage to which straps for this purpose are subjected.

45 It is also to be noted that the stitching of the intermediate portions of the respective straps form loops which receive the rings 7 and 8 respectively at the lower ends of the straps and additional loops at the upper ends 50 of the straps adapted to receive the rings

14, which rings are in turn connected through the medium of a head strap 15 as illustrated. The head strap 15 is looped or bent upon itself to receive the said rings 14—14 and as in the case of the chin strap it is provided 55 throughout a portion of its length with suitably spaced openings 16 for engagement with the tongue of the buckle 17, which is secured upon one end of the strap, thus permitting the lengthening of the strap as desired.

A movable ring 18 is movably mounted upon the chin strap 9 and the strap 19 constituting the throat latch is looped or bent upon itself as illustrated to receive one of 65 the rings 14, and as illustrated the throat latch strap 19 is doubled through the ring 18 and has slidably thereon a snap hook 20, engageable with the other of the said rings 14 to hold the latch strap in operative position. 70 Adjacent one end of course the strap is provided with suitable spaced apertures formed thereon for engagement with the tongue of a buckle 21, in the usual manner. Thus it is to be noted that the latch strap is also adjustable. 75

Frame members 22 have the throat latch strap 19 threaded therethrough respectively and these frame members are adapted to be adjustably disposed with respect to the strap 80 19 adjacent those portions of the strap adjacent the buckle 14. For the sake of clearness, it may be well to mention that these adjustable frame members 22 comprise a substantially rectangular body including spaced parallel side bars, and end bars connecting the side bars and between which side bars is a longitudinal bar having an upwardly extending pin or stud, receivable in suitable openings formed in the strap 19, for maintaining 85 the frame in an adjusted position upon the strap.

A jaw strap 23 is provided at opposite ends with loops 24, to receive the looped extensions 25, formed on each of said frames 90 22. Thus it will be seen that the jaw strap 23 may be moved lengthwise at its opposite end of the strap 19, the jaw strap thus being moved up or down with respect to the jaw of the animal to which the halter may be placed 100

to snugly extend about the jaw of the animals. My improved halter is exceedingly strong and durable, may be readily manufactured at slight cost, is very serviceable and 5 may be readily adjusted and also easily put on or taken off from the head of a horse or cow or other animal, wherein a halter of this nature may prove useful for purposes obvious to the user.

10 Even though I have herein shown and described, the preferred embodiment of my invention, it is to be understood that the same is susceptible to certain changes fully comprehended by the spirit of the invention and the 15 scope of the appended claims.

What is claimed is:

1. In a halter of the class described, a nose strap, cheek straps, rings connecting the nose strap and the cheek straps, a head strap, 20 rings connecting the head strap and the cheek straps; a chin strap connected to the first mentioned rings, a ring movable on the chin strap, a throat latch formed of a single strap connected to the second mentioned rings and 25 passing through said movable ring, a jaw strap, and means connecting the jaw strap with the throat latch, said connecting means being slidable on said throat latch.

2. In a halter of the class described, nose 30 strap, cheek straps, rings connecting the nose strap to the cheek straps, a head strap, rings connecting the head strap to the cheek straps, a chin strap formed from a single piece of material passed through the first mentioned 35 ring, and looped upon itself and provided with means for adjustably connecting the ends of the strap, a ring movable on the chin strap, a throat latch formed of a single strap connected to the second mentioned ring 40 and doubled through said movable ring, adjustable means connecting the ends of the throat latch strap, a pair of frame members 45 slidable on the throat latch strap, and a jaw strap having its ends secured to the respective frame members.

3. In a halter of the class described, a nose strap, a head strap, cheek straps connected to the nose strap and head strap respectively, and adjustable chin strap, rings connecting 50 said nose, cheek and chin strap, a ring movable on the chin strap, an adjustable throat latch strap, rings connecting said head, cheek and throat latch straps, said throat latch strap adapted to pass through said movable ring, and a jaw strap slidably and adjustably 55 associated with said throat latch strap.

In testimony whereof I affix my signature.
IVANHOE WINSLOW.
